UNITED STATES PATENT OFFICE.

JOHN NELSON, OF OTTAWA, KANSAS.

REINFORCED-CONCRETE TIE.

1,318,904.

Specification of Letters Patent.

Patented Oct. 14, 1919.

Application filed July 18, 1919. Serial No. 311,803.

To all whom it may concern:

Be it known that I, JOHN NELSON, a citizen of the United States of America, residing at Ottawa, in the county of Franklin and State of Kansas, have invented certain new and useful Improvements in Reinforced-Concrete Ties, of which the following is a specification.

The primary object of the invention is 10 the provision of a railway tie that has long life, is easy and inexpensive to manufacture, and adapted for laying upon a road-bed in track formation with great rapidity.

Another object of the invention is to provide an essentially concrete tie having a 15 special form of metal reinforcement for strengthening the concrete structure and affording a metal seat for the rails which are accurately gaged by such reinforcement, a rail fastener being also included as a part of the invention.

A still further object is to provide a metal 20 reinforcing member for concrete ties and the like, which member being formed of sheet metal is easily stamped and bent into shape affording strong anchoring means for the surrounding cement body as well as providing a metal seat and outer fasteners for the rails positioned for use upon the tie.

With these general objects in view, the 25 invention consists of the novel combination and arrangement of parts, hereinafter more fully described, illustrated in the accompanying drawing and then claimed.

In the drawing forming a part of this 30 application, and in which like reference characters designate corresponding parts throughout the several views,

Figure 1 is a side elevation of the invention 35 with rails shown in vertical transverse section, operatively secured thereon.

Fig. 2 is a top plan view thereof partially cut away through the concrete with one rail in position shown in horizontal longitudinal 40 section.

Fig. 3 is a vertical longitudinal sectional view of an end portion of the invention upon an enlarged scale.

Fig. 4 is a vertical transverse sectional 45 view through the tie, taken upon line IV-IV of Fig. 1 and

Fig. 5 is an elevational view of a portion of the blank forming the metal reinforce before bending the same.

Referring more in detail to the drawing, 50 my invention comprises a sheet metal rein-

forcing member 10 embedded in a body 11 of plastic composition of proper length for a railway tie and rectangular in cross section being substantially of the same exterior 60 form and size of the ordinary wooden tie now in use. The sheet metal member 10 is of slightly less length than the tie to be formed and has one entire edge 12 provided with equally spaced slits 13 forming ears 65 14 adapted for alternate bending in opposite directions perpendicular to the body of the member 10.

Spaced extensions 15 are formed on the member 10 in making the same by means 70 of a die or otherwise, the said extensions having their upper spaces 16 adapted for lying flush with the top or upper surface 17 of the completed cement tie for seating railway rails 18 transversely thereon. Inwardly projecting curved ears 19 upon the outer ends of the extensions 15 are adapted to overlie the outer base flanges 20 of the rails 18 for spacing the rails the required gaged distance apart accurately positioned 75 in track formation.

The opposite edge 12' of the blank 10 from said edge 12 is provided with similar slits 13' between and outwardly of the extensions 15 forming ears 14' for alternate bending 80 in opposite directions for anchoring the metal member in the concrete.

Cooperating fasteners are provided inwardly of the rails 18 for use with the ears 19, the same consisting of inwardly projecting 90 arms 21 upon the extensions 15 with bolts 22 mounted upright on said arms by means of longitudinal slots 23 in the bolts, through which the arms 21 extend. The bolts 22 are in this way mounted parallel to 95 the adjacent inner edges of the extensions 15 and the inner free ends of said arms are preferably curved laterally as at 24, said arms and the enlarged lower slotted end portions or heads 25 of said bolts being 100 firmly embedded in the concrete 11 and anchored in position in the formation of the completed tie.

The bolts 22 project above the top 17 of the tie sufficiently spaced from the ears 19 to permit the rails 18 to be freely positioned upon the seat 16 with the outer flanges of the rails beneath said ears 19. A detachable clamp or fastener 26 is then positioned upon each bolt 22 seated partially upon the top 17 of the concrete and partly upon the metal seat 16 of the adjacent extension 15

and a lock nut 27 then threaded upon the upper end of each bolt 22 for securing the clamps 26 with the rail mounted for use transversely of the tie.

5 The metal reinforce 10 is securely anchored by the ears 14 and 14' within the concrete 11 which is molded or formed in any usual manner such as by pouring into a mold not shown entirely covering the main 10 portion of said member with the faces 16 and ears 19 of the extensions 15 alone exposed, such exposures being at the top 17 of the tie or concrete block 11 for the purposes heretofore noted. The vibrations 15 incident to the operation of the railroad will be taken up by the metal member 10 thereby insuring long life to the concrete portion 11 of the tie as well as strengthening the concrete against vertical stresses as well as 20 lateral and longitudinal stresses by the relative perpendicular relations between the main portions of the member 10 and the ears 14, 14'.

While the form of the invention herein 25 set forth and described is believed to be the preferred embodiment thereof, it will be nevertheless understood that minor changes may be made therein without departing from the spirit and scope of the invention 30 as claimed.

What I claim as new is:

1. A railway tie comprising a sheet metal strip having transverse slits in its opposite edges forming intervening ears adapted for 35 alternate bending in opposite directions

forming anchoring members, a concrete body in which said strip is embedded having an upper face adapted for mounting railway ties thereon, integral extensions upon said strip with their upper edges flush 40 with the top of said concrete body and having ear portions above said body adapted for engaging the outer flanges of rails when positioned upon the tie and adjustable rail holders for the inner flanges of the rails 45 attached to said extensions at points within the concrete body.

2. A railway tie comprising a rectangular concrete body having its upper face adapted for the transverse seating of rails thereon, 50 a metal reinforcing member comprising an elongated sheet metal strip embedded in said body with oppositely projecting anchoring portions at its upper and lower edges, integral extensions upon said strip 55 with their upper edges flush with the top of said body adapted for seating the rails thereon, inwardly projecting ears at the outer edges of said extensions for engaging the outer flanges of rails, inwardly projecting curved arms upon the inner edges of the extensions within said body, bolts positioned upright in the body having eyes mounted upon said arms and clamps removably secured upon said bolts adapted for overlying 60 the inner flanges of rails when positioned in track formation upon the device.

In testimony whereof I affix my signature.

JOHN NELSON.
